PUSH-ON RETAINERS

Hyman Kramer, 2764 E. 16th St., Brooklyn, N.Y.
Filed Nov. 24, 1964, Ser. No. 413,509
4 Claims. (Cl. 85—35)

The present application for Letters Patent is, particularly in its article aspect, a continuation-in-part of application Serial No. 327,672, filed December 3, 1963, now Patent No. 3,215,025.

This invention relates to improvements in push-on retainers and is more particularly directed to an end cap-type retaining device which is adapted to secure itself in end-capping relation to a shaft, spindle or like carrier member when simply pushed over the end thereof.

Continuing experience with end-cap type retainers presently available on the market as well as with the various improved forms thereof according to my aforesaid application, has demonstrated a feature of objection common to all, namely, that of the difficulty in initially centering them and thereafter engaging them with their carrier members due to the interference to centering and motion of retainer on carrier end stemming from the location of the locking prongs with which said retainers are provided and on whose action depends the holding power of the retainers with respect to their carrier members. In explanation, in the prior forms and makes of push-on retainers, it was conventional to locate the locking prongs thereof so that their inner free ends which project into the interior of the retainer crown portion are disposed closely adjacent the juncture of said crown portion with the brim or washer-like flange portion thereof. In this location, the inner ends of the locking prongs exert a degree of resistance to initial centering of the retainer on carrier-member end which can be substantial if the internal diameter of the retainer crown portion closely approximates the external diameter of the carrier member, which again is necessary for proper locking action of the prongs. And if the retainers are not properly centered initially, either an undue amount of force is required to finally set them or they are likely to assume a cocked position on their carrier members when finally pushed to their final position, which latter is highly objectionable.

A main object of the present invention, therefore, is the provision of a push-on end cap-type of retainer constructed and arranged as to overcome the above-noted objectionable feature of the prior retainer of similar type.

A more particular object of the invention is the provision of a push-on end cap-type of retainer whose locking prongs are effectively located nearer the closed end of the crown portion thereof than are the locking prongs of the prior retainers of similar type, which results in appreciable unobstructed axial space being provided at the end of the crown portion adjacent the brim or washer-like flange portion of the device, as in turn facilitates initial centering of the retainer on a shaft, spindle or like carrier-member end.

The above and other objects and advantages of the present invention will appear from the following more detailed description thereof, in which reference is had to the accompanying illustrative drawings, wherein:

FIG. 1 is a plan view of a push-on end cap-type retainer according to the invention, looking into the open end of the crown portion and thus onto the under or working face of the brim or retaining flange portion thereof;

FIGS. 2 and 3 are sections taken on lines 2—2 and 3—3, respectively, of FIG. 1;

FIG. 4 is a greatly enlarged fragmentary perspective view, looking into one of the crown embossments and onto the inside face of one of the locking prongs of a

2

push-on end cap-type retainer of the invention, this view being intended to illustrate the substantial setting-back of the locking prongs within the crown portion thereof which characterizes the retainer of the invention;

5 FIG. 5 is a plan view which illustrates the progressive formation of push-on end cap-type retainers of the invention from a strip of suitable retainer material such as sheet steel; and

FIG. 6 is a section taken along line 6—6 of FIG. 5.

Referring to FIGS. 1-4, such illustrate that a push-on end cap-type retainer of the invention basically comprises a cap or crown portion 10, an integral brim or retaining-flange portion 12 (said portions to be hereinafter for convenience referred to as the crown and the retaining flange, respectively) and circumferentially spaced (usually diametrically opposed) integral locking prongs 14a, 14b whose free ends extend radially and along arcs of a circle of lesser diameter than that of the crown interior into the interior space of said crown 10 by an amount and at an inclination such as to permit the retainer to be readily pushed onto the end of a shaft, spindle or like carrier member having diameter slightly less than that of the internal diameter of the crown 10, and thereafter to enable the retainer to self-lock itself to said carrier member by virtue of the ability of the arcuate free-end edges of the locking prongs to bite into the material making up the peripheral surface of said member, under a thrust force or forces directed against the under face of the retaining flange and acting in a direction as tends to separate the retainer as a whole from said carrier member.

According to the present invention, the integral locking prongs 14a, 14b, rather than being struck out from the material of the crown and/or brim at locations thereof such that they flex about root lines disposed either within the area of the retaining flange or which substantially coincide with the line of juncture between the crown and retaining flange, as is conventional in the prior push-on end cap-type retainers, are instead not only struck out from portions of the crown wall which are spaced a substantial distance axially inwardly or toward the closed end 10a of the crown so that the prongs flex about root lines which are set back into the crown, but also are struck out from the material of radially outwardly projecting bulges or embossments purposefully formed in the crown wall at diametrically opposed locations thereof, thus to space said root lines outwardly of the circle of the crown. It will be understood that the expression "root lines" as herein used means the imaginary lines which extend across the roots of the prongs at the junctures of said prongs and the part, i.e. crown, retaining flange and/or embossments to be described, from which said prongs extend and about which said prongs flex.

More particularly, it is a feature of the invention that outwardly projecting embossments designated 18 and 20 in the various views are formed in the crown wall and retaining flange at preferably diametrically opposite areas thereof by drawing same from the metal of the crown wall and retaining flange beginning substantially inwardly of the plane of the retaining flange 12 and extending radially outwardly into said flange. As best seen in FIG. 4, said embossments 18 and 20 are each defined by circumferentially spaced-apart side walls a, b, a connecting outer wall c and an end wall d which merges into the crown wall at a location which is spaced a substantial distance inwardly of the crown from the line of juncture of said crown and said retaining flange. Thus, the embossments 18, 20 each has general U-section in both transverse and vertical planes extending through same and, as will be evident from a consideration of FIG. 4 in particular, the embossments open both into the crown interior and downwardly through the retaining flange 12.

Upon formation of the embossments 18, 20 as aforesaid,

it becomes a relatively simple matter to form the locking prongs 14a, 14b by in effect cutting the end walls d of the embossments away from both crown walls with which they merge and from the embossment side walls a, b to which said end walls were earlier integrally joined, along generally U-shaped lines of cut designated 14c in FIG. 2. Preferably, the transverse lines of cut separating the embossment end walls d from the crown wall, rather than being disposed precisely at the juncture of said end walls d and the crown wall, are disposed a small distance away from said juncture in the direction of the crown end wall 10a, thus to give some added length to the locking prongs being so formed, and the side lines of cut extend back into the embossment side walls for a depth such as to provide a workable prong. Such cutting-away operation frees the inner end portions of the embossment end walls d both from the embossment side walls a and b and from the crown wall, so that such end portions now tend to assume the configuration of conventional prongs. Finally, the so cut-free prongs are given the requisite inclination as enables them to act as locking prongs, that is to say, they are "coned" inwardly into the crown interior space at an angle which does not exceed the so-called "friction angle." By the term "friction angle" as here employed is meant the angle which enables the locking prongs 14a, 14b to flex radially outwardly more or less freely when the retainer is being pushed onto the end of its carrier member in its assembly thereon, but to straighten and thereby the free-end edges thereof to bite into and grip to the material making up the peripheral surface of the carrier member when a thrust force is applied to the retaining flange 12 in direction as tends to cause the retainer as a whole to move axially away from and separate itself from said carrier member.

Push-on end cap-type retaining devices according to the present invention are thus characterized by locking prongs which project into the interior space of the crown or cap portion at locations along the axial dimension thereof which are spaced a substantial distance from the plane of the retaining flange portion of such devices. Hence, end cap-type retaining devices as herein constructed and arranged can be more readily initially centered on and moved over the ends of their shafts, spindles and the like than was possible with the prior retaining devices of similar type whose locking prongs projected into the circle defining the interior space of the crown portion thereof at locations closely adjacent the juncture of the crown and retaining flange portions thereof, with the result that said locking prongs interfered with both the quick and easy initial centering and the final placement of the retainer on its shaft or other carrier member.

Push-on end cap retaining devices according to the invention lend themselves to cheap, speedy manufacture from a strip ST of sheet steel of the proper gauge in a progressive compound blanking, drawing and piercing die. While such a die is not shown, its progressive action in blanking out each starting disc-form blank SD from which an end cap as herein proposed is ultimately fashioned, in progressively deep-drawing the crown portion 10 in a plurality of stages (in practice four successive draws) from said blank, in further drawing the diametrically opposed, radially-outwardly projecting embossments 18, 20 from side wall areas of the crown portion and adjacent areas of the blank, in piercing said embossments and crown wall in manner as to cut the locking prongs 14a, 14b therefrom as the strip is moved progressively through the die, and finally in cutting away the finished cap-type fastener from its blank, will, it is believed, be readily apparent to persons skilled in the art from a consideration of FIGS. 5 and 6. As also diagrammatically shown in said views, it will be understood that the end-cap blanks from the starting disc blanking-out stage thereof through the prong-piercing or cutting-out stage are connected to the strip ST at diametrically opposed portions thereof by connecting webs W, W₁, and

5 that the final end caps are struck out from said blanks along circular lines of severance lying within the outer part-circular lines of cut which define said blanks. It will also be observed that the embossments 18, 20 are formed on the same diameter as that of the webs W, W₁ which connect the blanks SD to the strip, a feature designed to insure adequate metal into which the embossment bottom portions may extend. Preferably, the bending of the locking prongs 14a, 14b to their proper "coning angle" is also effected in the die, so that the end caps struck from the blanks may be removed from the die as completed articles separately from the scrap discharging therefrom.

10 While the cap-type retainer of the invention has been described and illustrated as having a closed crown top or inner end 10a, it may also be fashioned without said top or with an apertured top, thus to be movable to any desired axial position along the length of a shaft, spindle or like carrier member required for a particular fastener application. It is also within the scope and purview of the present invention to arrange the locking prongs 14a, 14b so that they lie on a helix corresponding to the pitch of the threads of a bolt, in which case a retainer according to the invention is capable of serving as a push-on 15 securing nut for said bolt.

20 Without further analysis, it will be appreciated that push-on end cap-type retainers according to the invention satisfies the objectives of the invention in effective and thoroughly dependable manner. However, as many changes could be made in carrying out the above constructions without departing from the scope of the invention, it is intended that all matter contained in the above description or shown in the accompanying drawings shall be interpreted as illustrative and not in a limiting 25 sense.

30 35 I claim:

1. An end cap-type retainer device for push-on assembly on the end of a shaft and like carrier member comprising: a cap-form body having a substantially cylindrical crown portion defining a shaft-receiving opening and an integral brim-like retaining flange extending radially outwardly from an end thereof and adapted to take thrust loads applied in axial direction against its under face, a plurality of circumferentially spaced, radially outwardly projecting embossments formed in the side wall of said crown portion and terminating at their ends remote from said flange in substantially plane end walls, and locking prongs comprising areas struck out from at least said end walls and having length such that their free ends extend radially inwardly into the interior space of said crown portion, and said locking prongs further having inclination such that said prongs will flex outwardly during push-on assembly of the device on said carrier member but will tend to assume radial positions in which the free-end edges thereof bite into the material of the peripheral surface of said member when thrust loads are applied to the under face of said retaining flange as aforesaid.
